UNITED STATES PATENT OFFICE.

EDGAR L. WILLIAMS, OF PEORIA, ILLINOIS, ASSIGNOR TO THE ARCHARENA COMPANY, OF SAME PLACE.

DESIGN FOR A SPINNING-TOP.

SPECIFICATION forming part of Design No. 33,056, dated August 14, 1900.

Application filed June 6, 1900. Serial No. 19,332. Term of patent 14 years.

To all whom it may concern:

Be it known that I, EDGAR L. WILLIAMS, a citizen of the United States, residing at Peoria, in the county of Peoria and State of Illinois, have invented and produced a new and original Design for a Spinning-Top; and I do hereby declare that the following is a full, clear, and exact description of the invention, which will enable others skilled in the art to o which it appertains to make and use the same.

This invention pertains to a new design for a spinning-top.

In the annexed drawings, Figure 1 is an elevation of the top. Fig. 2 is a plan view 5 thereof.

The design consists of a body A, which is circular in cross-section and of greater dimensions longitudinally than laterally. It is pro-

vided at the top with a stem B, which gradually increases in size until it meets the body, 20 where it widens or spreads and terminates in a shoulder C. From said shoulder the body widens and then by a short shoulder descends in a long curve, which forms the sides. The latter terminate in a rounded base, or a 25 base having no point or projection.

I claim—

The design for a spinning-top substantially as shown and described.

In testimony whereof I affix my signature 30 in presence of two witnesses.

EDGAR L. WILLIAMS.

Witnesses:

C. C. HARPER,
C. F. CHILDRESS.
